UNITED STATES PATENT OFFICE.

JOHN HAYS HAMMOND, JR., OF GLOUCESTER, MASSACHUSETTS.

PIANO-MODULATOR-CONTROL DEVICE.

Application filed April 8, 1925. Serial No. 21,483.

This invention relates to improvements in musical instruments of the percussive type and more particularly to improved control devices for tone modulators for such instruments.

It is one object of the present invention to provide an improved stringed musical instrument including a plurality of tuned strings positioned within a sound insulated

10 casing and having means forming part of the casing for variably controlling the intensity of sound emitted therefrom, and to provide an improved pedal device for operating said means.

15 An important feature of the invention relates to the combination of an instrument having a soft pedal or pianissimo action and improved modulating means, and a control device to operate them, either independently or together, to improve the control of the musical effects produced by the instrument.

Other objects will appear from the following description taken in connection with the accompanying drawings in which:

20 Fig. 1 is a front elevation partly in section of a piano embodying features of the invention, the section being taken on the line 1—1 of the Figure 2;

25 Fig. 2 is a sectional view taken on the line 2—2 of Fig. 1;

Fig. 3 is a detailed view of the operating mechanism of the structure shown in Fig. 2 when adjusted to one of its positions; and

30 Fig. 4 is a detailed view of the parts illustrated in Fig. 3 when adjusted in a different position.

Like reference characters refer to like parts in the several figures of the drawing.

35 In the following description and claims parts will be identified by specific names for convenience of expression, but they are intended to be as generic in their application to similar parts or equivalent construction as the art will permit.

40 Referring to the accompanying drawings, there is shown a musical instrument of the percussive type, that shown being a grand piano 10, provided with usual pedals 11, 12 and 13, which are mounted in a frame depending from the main portion of the piano. The frame consists of a block 14, carried by a pair of upright side members 15 and 16, secured at their upper ends to a second block 17. The block 17 is supported on a member 18 secured to the body of the piano. The pedals 12 and 13 are operatively inter-

connected to two rods 20 and 21, which control the sostenuto and loud pedal actions of the piano in a well known manner.

The volume of sound emitted from the piano may be variably controlled by means of the soft or pianissimo action of the piano whereby the position of the percussive means with respect to the strings is adjusted by the pedal 11.

45 The pedal 11 is operatively connected to a rod 22 which passes through the block 17 and to which is rigidly secured a collar 23. Loosely mounted on the rod 22 and resting on the collar 23 is a member 24 which is provided with a lug 25, which cooperates with one arm of a bell-crank 26 which is pivoted at 27 to the member 18. The other end of the bell-crank 26 passes through a slot in the piano casing and engages a recess 28 in the bed of the key action 30. This bed is slidably mounted on the framework of the piano and is held to the left by means of a spring 31. Movement of the pedal 11 thus adjusts the position of the hammers of the piano action 30 relative to the strings.

50 The lug 25 also cooperates with a bell-crank 33 which is pivoted at 34 to the member 18. Pins 35 and 36 are provided which act as stops for the bell-cranks 26 and 33. The other end of the bell-crank 33 is connected to a link 37, the other end of which is pivoted to an arm 38 rigidly secured to a shaft 40 which is supported in bearings 41 and 42. Rigidly secured to the shaft 40 is a collar 43 which prevents it from sliding through the bearings 41 and 42. One end of a spring 44 is attached to the link 37 and the other end is secured to a bracket 45, mounted on the framework of the piano.

55 For varying the intensity of sound emitted from the instrument independently of the percussion of the strings and thus without affecting the harmonics of the tones produced by the strings, there is provided tone modulating mechanism which will now be described.

60 Rigidly secured to the shaft 40 is an arm 46 to which is pivoted a link 47 the other end of which is connected to a rod 48. Pivoted to the rod 48 is a plurality of arms 50, mounted upon an equal number of tone modulators 51, which are pivoted for rotation about their longitudinal axes in the framework of the piano. Rigidly secured to the top of the shaft 40 is an arm 52 to which is pivoted a link 53 the other end of

which is connected to a rod 54. To the rod 54 is pivoted a plurality of arms 55 which are mounted on an equal number of tone modulators 56 which are pivoted in the framework of the piano.

The modulators 56 are mounted over the strings 60 which are carried by the frame 61. A suitable piano action 62 is provided which is operated in a well known manner from the keys 63. The action 62 includes a striking hammer which delivers a sharp, quick blow to the strings when the respective key is actuated, thus causing the strings to vibrate and produce a musical note. The casing of the piano is substantially sound-proof so that when the modulators 51 are closed, the minimum of musical tone is emitted from the instrument.

For rotating the member 24, there is provided on it a second lug 65 (see Figures 2, 3 and 4) which is pivoted to a link 66 the other end of which is connected to an arm 67 which is rigidly secured to a shaft 68, which is mounted for rotation in the bearings 70 and 71. At the end of the shaft 68 is rigidly secured a handle 72. Rigidly secured to the middle of the shaft 68 is an impulsive stop device, preferably consisting of a clicker segment 73 and provided with three notches which cooperate with a clicker 74 secured to the framework of the piano.

In the operation of this invention when the soft pedal 11 is depressed the rod 22 is lifted, thereby lifting the collar 23 and the member 24, this causes the bell-crank 26 to be rotated in a clockwise direction thus moving the keyboard 30 to the right against the action of the spring 31, this throws on the standard soft pedal action of the piano. At the same time the bell-crank 33 is rotated in a counter-clockwise direction, as seen in Fig. 1. This causes both of the links 47 and 53 to be moved to the right which by means of the rods 48 and 54 causes the modulators 51 and 56 to be closed.

If it is desired to operate the modulators without throwing on the soft pedal action, the handle 72 is moved to the left thereby moving the link 66 to the right and rotating the member 24 in a clockwise direction from the position shown in Fig. 2, to that shown in Fig. 3. This will throw the lug 25 out of alignment with the bell-crank 26 so that when the soft pedal 11 is depressed, it will only operate the bell-crank 33 thus closing the modulators without affecting the soft pedal action.

If it is desired to operate only the soft pedal action without affecting the modulators, the handle 72 is moved to the right, thereby rotating the member 24 in a counter-clockwise direction which moves the lug 25 out of alignment with the bell-crank 33, so that when the soft pedal 11 is depressed it will only operate the bell-crank 26 to throw

on the standard soft pedal action, as shown in Fig. 4.

Thus it will be seen that I have provided a modulating system particularly well adapted for musical instruments of the percussive type by means of which the intensity of sound emitted from the instrument may be varied in a variety of ways to introduce novel effects in the music. I have found that by the use of the present invention exceedingly important musical effects are produced, as the dynamics and tone color may be very effectively varied in a manner hitherto impossible upon standard piano-forte. Furthermore the sound produced by a string may be varied as may be desired while the note is sustained, and thus a wide variety of dynamic variations may be employed. A maximum pianissimo effect can be produced through the conjoint action of the above described mechanisms.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

What I claim is:

1. In a musical instrument of the percussive type, a plurality of hammers, strings arranged to be set into vibration by the impact thereon of said hammers, a plurality of keys for actuating said hammers respectively, means for variably positioning said hammers with respect to said strings to modify the intensity of sound produced by said strings by the impact of the hammers, a plurality of tone modulators for varying the intensity of sound emitted from the instrument independently of said hammer positioning mechanism, and means for selectively operating either the hammer positioning mechanism or the independent modulating mechanism.

2. In a musical instrument of the percussive type, a plurality of hammers, strings arranged to be set into vibration by the impact thereon of said hammers, a plurality of keys for actuating said hammers respectively, means for variably positioning said hammers with respect to said strings to modify the intensity of sound produced by said strings by the impact of the hammers, a plurality of tone modulators for varying the intensity of sound emitted from the instrument, independently of said hammer positioning mechanism, a sound intensity control device, and means for operatively connecting said device either to the hammer positioning means or to the tone modulators selectively.

3. In a musical instrument of the percus-

sive type, a plurality of hammers, strings arranged to be set into vibration by the impact thereon of said hammers, a plurality of keys for actuating said hammers respectively, means for variably positioning said hammers with respect to said strings to modify the intensity of sound produced by said strings by the impact of the hammers, a plurality of tone modulators for varying the intensity of sound emitted from the instrument independently of said hammer positioning mechanism, a sound intensity control pedal, and a selector device for operatively connecting said pedal to the hammer positioning means or to the tone modulators, or to both.

4. In a musical instrument of the percussive type, a plurality of hammers, strings arranged to be set into vibration by the impact of the hammers thereon, a pianissimo action for reducing the effect of the impact of said hammers on the strings, a tone modulating device for regulating the volume of sound emitted from the instrument a pedal, and selecting means for operatively interconnecting the pedal to either the pianissimo action or to the tone modulating device or to both.

5. In a musical instrument of the percussive type, means effective at the moment of percussion for controlling the volume of sound produced from the instrument, additional means effective at any time during the production of sound for controlling the volume of sound produced from the instrument, a pedal, and a selector mechanism for operatively interconnecting the pedal with either or both of said sound controlling means.

6. In a musical instrument the combination with a piano having a pianissimo action of a plurality of shutters for variably controlling the intensity of sustained notes, a pedal, and a selector mechanism for operatively interconnecting the pedal with said pianissimo action or with said shutters selectively.

7. In a musical instrument, the combination with a piano having a pianissimo action, of a plurality of shutters for variably controlling the intensity of sustained notes, a pedal, and a selector mechanism for operatively interconnecting the pedal with said pianissimo action or with said shutters or with both.

8. In a musical instrument of the percussive type, the combination with strings and a plurality of hammers for setting said strings into vibration by percussion, of a casing having oppositely disposed apertures and substantially soundproof boundary walls intermediate said apertures, movable closures for apertures, a pianissimo action for controlling the hammers to vary the initial intensity of sound when the strings are set into vibration, a control pedal, and selec-

tor mechanism for operatively interconnecting said pedal with said pianissimo action or with said movable closures selectively.

9. In a musical instrument, the combination of strings, means for vibrating said strings by percussion, a pianissimo action for controlling the position of said vibrating means with respect to said strings, of a sound insulating body portion for suppressing the sound produced by the strings, said body portion having movable closures effective for controlling the volume of sound emitted from the instrument, a pedal, and a selector device interposed between said pedal and said pianissimo action and movable closures whereby the operation of said action and closures may be selectively controlled by said pedal.

10. In a musical instrument, the combination with strings and means for vibrating the strings by percussion, of a sound insulating body for effectively suppressing the sound produced by the vibration of said strings, means for variably controlling the passage of sound from within said body, a control pedal, and selector mechanism interposed between said pedal and said vibrating means and said sound control means.

11. In a musical instrument having hammer control mechanism and a pedal for controlling said mechanism, a plurality of shutters for varying the volume of sound emitted from said piano, and means interconnecting said shutters and said pedal for actuating said shutters independently of, or simultaneously with, said hammer control mechanism selectively.

12. In a musical instrument having hammer control mechanism and a pedal for controlling said mechanism, a plurality of shutters for varying the volume of sound emitted from said piano, a control device, and means controlled by said device for operatively interconnecting said pedal with said hammer control mechanism or said shutters selectively.

13. In a musical instrument having hammer control mechanism and a pedal for controlling said mechanism, a plurality of shutters for varying the volume of sound emitted from said piano, a control device, and means controlled by said device for operatively interconnecting said pedal with said hammer control mechanism or said shutters or both.

14. In a musical instrument of the percussive type, a plurality of hammers, strings arranged to be set into vibration by the impact thereon of said hammers, a plurality of keys for actuating said hammers respectively, means for variably positioning said hammers with respect to said strings to modify the intensity of sound produced by said strings by the impact of hammers, a plurality of tone modulators for varying the

intensity of sound emitted from the instrument independently of said hammer positioning mechanism, a sound intensity control device, and means for operatively connecting said device either to the hammer positioning means or to the tone modulators selectively.

15. In a musical instrument of the percussive type, a plurality of hammers, strings arranged to be set into vibration by the impact of the hammers thereon, a pianissimo action for reducing the effect of the impact of said hammers on the strings, a tone modulating device for regulating the volume of sound emitted from the instrument, a controller operable at will, and selecting means for operatively interconnecting said controller to either the pianissimo action or

to the tone modulating device or to both.

16. In a musical instrument of the percussive type, means effective at the moment of percussion for controlling the volume of sound produced from the instrument, additional means effective at any time during the production of sound for controlling the volume of sound produced from the instrument, a device movable at the will of an operator, and a selector mechanism for operatively interconnecting said device with either or both of said sound controlling means.

Signed at New York city in the county of New York and State of New York this 7th day of April, A. D. 1925.

JOHN HAYS HAMMOND, JR.
